UNITED STATES PATENT OFFICE.

GUSTAVE L. SCHMALL, OF NEW HARMONY, INDIANA.

COLLAPSIBLE EGG-SHIPPING CASE.

1,051,274.

Specification of Letters Patent. Patented Jan. 21, 1913.

Application filed October 5, 1910. Serial No. 535,491.

To all whom it may concern:

Be it known that I, GUSTAVE L. SCHMALL, a citizen of the United States, residing at New Harmony, in the county of Posey and 5 State of Indiana, have invented new and useful Improvements in Collapsible Egg-Shipping Cases, of which the following is a specification.

This invention relates to metallic collapsible crates, primarily intended for use in the shipment of eggs, and the principal object of the invention is to provide a device of this character which, when the contents thereof are removed, may be folded into 15 a small compass, so as to be readily packed within the car for shipping.

Another object of the invention is to provide a metallic collapsible box of this character comprising few parts, all of which being connected together so that liability of 20 loss of any of the parts is entirely obviated.

A still further object of the invention is to provide a device of this class comprising a pair of compartments, the said compartments being divided from each other by a hinged partition and each of the compartments being provided with a hinged bottom portion which is adapted, when the hinged 25 edges of the members comprising the compartments are in their set-up position, to swing downwardly and sustain the crate in its said set-up position.

With the above, and other objects in view, which will appear as the description progresses, the invention resides in the novel construction and combination of parts hereinafter fully described and claimed.

In the accompanying drawings, Figure 1 is a perspective view of a crate constructed 40 in accordance with the present invention and showing the cover in its raised position. Fig. 2 is a similar view illustrating the device in its partially collapsed position. Fig. 3 is a transverse sectional view taken 45 through one of the compartments, the device being in its set-up position. Fig. 4 is a detail transverse sectional view taken through the opposite compartment. Fig. 5 is a detail horizontal sectional view upon the 50 line 5—5 of Fig. 1. Fig. 6 is a top plan view of the crate, the door being in its open position.

In the accompanying drawings the numeral 1 designates the improved metallic 55 shipping crate. This crate 1, when in its set-up position, comprises a substantially

rectangular device comprising the elongated front and rear 2 and 3 respectively, and the ends 4 and 5 as well as a central partition 6. The ends 4 and 5 have their vertical edges hingedly connected with the front and rear 2 and 3, as designated by the numeral 7, and as clearly illustrated in the figures of the drawing. The front and rear 2 and 3 are centrally and vertically cut 60 away as at 8, a distance sufficient for the reception of the butt 9 formed upon the partition 6. Secured to the portion of the front and rear members 2 and 3, at the opposite ends of the cut-away portions 8 are bearing 65 plates 10 and 11 adapted for the reception of the pintles 12 which engage the butt upon the edges of the partition. By this arrangement, it will be noted that the upper and lower portions of the edges of the partition 70 6 are retained within the crate and that the said partition will fold snugly between the members of the partition when the device is collapsed as illustrated in Fig. 2 of the drawings. The partition divides the crate 80 into a pair of compartments 13 and 14 and each of the said compartments is provided with floors 15 and 16. These floors 15 and 16 are hinged in opposite directions, as 75 clearly illustrated in the plan view of the drawings, and each of the said floors adjacent its hinged connection with the portion of the members 2 and 3 within the compartment are provided with depending lips 17 and 18, while the lower extremities of the 85 said members 2 and 3 opposite to their hinged connections with the floors are formed with upstanding ledges 19 and 20 which are adapted to engage the lips of the 90 oppositely pivoted floors when the latter are 95 swung in their closed position. It is, of course to be understood that the floors 15 and 16 are of a diameter equaling the compartments and snugly engage all the sides thereof so that the structure is effectively 100 retained in its set-up position by the said floors and the engagement of the lips of the floors with the ledges or flanges 19 and 20. Each of the floors 15 and 16 is provided 105 with cleats 23 and 24, the same being adapted to strengthen the said floors and to prevent the sagging or bulging of the same.

The crate 1 is provided with a closure or door 25, the same being hingedly connected with the rear 3 of the device and the 110 front edge of the said door 25 is provided with a plurality of perforations 26, the lat-

ter being adapted for the reception of ceiling wires 27 which also pass through perforations 28 arranged in the front 2 of the crate.

5 From the above description, taken in connection with the accompanying drawings, it will be noted that I have provided an extremely simple and effective device for the purpose intended, and while I have illustrated and described the preferred embodiment of the improvement, as it now appears to me, minor details of construction, within the scope of the following claim may be resorted to if desired.

10 15 Having thus fully described the invention, what I claim as new is:—

A metallic crate comprising a front, a back and ends hinged together at their edges, the front and back being centrally 20 provided with vertical slots, bearing plates

secured to the outer faces of the front and back and arranged at the opposite ends of said slots and having their inner ends flush with the end walls of said slots, a partition having butts extending through said slots 25 and projecting beyond said front and back, a pintle passing through the bearing plates and butts to hingedly connect the partition to the front and back oppositely hinged floors arranged within the compartment 30 formed by the partition, means for locking the said floors against displacement, and a cover hinged to the back.

In testimony whereof I affix my signature in presence of two witnesses.

GUSTAVE L. SCHMALL.
